UNITED STATES PATENT OFFICE.

FRANK J. KIMBALL, OF LOS ANGELES, CALIFORNIA, ASSIGNOR TO FRANK J. KIMBALL COMPANY, OF LOS ANGELES, CALIFORNIA, A CORPORATION OF CALIFORNIA.

INTERNAL-COMBUSTION ENGINE.

1,200,853.

Specification of Letters Patent. Patented Oct. 10, 1916.

Application filed June 27, 1914. Serial No. 847,570.

To all whom it may concern:

Be it known that I, FRANK J. KIMBALL, a citizen of the United States, residing at Los Angeles, in the county of Los Angeles and State of California, have invented a new and useful Internal-Combustion Engine, of which the following is a specification.

This invention relates to internal combustion engines of the type in which a charge of mixed fuel and air is compressed after it enters the cylinder, and the main object of the invention is to increase the expansion, in the expansion stroke of the engine, relatively to the compression in the compression stroke, so that the pressure at which the gases are discharged from the engine is reduced to a minimum, with resulting increase in efficiency of the engine.

Another object of the invention is to provide for utilization of low grade or heavy fuel, by forming a combustible mixture of such fuel with air, under sufficiently high pressure and temperature, to maintain the mixture, temporarily, in gaseous condition, then introducing a charge of such mixture into the cylinder of the engine and further compressing the same.

While my invention is applicable to internal combustion engines of any type, using charge compression, it is particularly applicable to engines of the two-cycle type, and an important object of the invention, in connection with such an engine, is to provide for thorough and effective scavenging of the cylinder by a positive scavenging action.

The accompanying drawings illustrate an embodiment of my invention and referring thereto: Figure 1 is a plan view of the engine. Fig. 2 is a longitudinal section on line x^2-x^2 in Fig. 1. Fig. 3 is partly broken side elevation of the mixture inlet means for the main cylinder. Fig. 4 is a section on line x^4-x^4 in Fig. 1. Fig. 5 is a section on line x^6-x^5 in Fig. 1. Fig. 6 is a side elevation partly broken away. Fig. 7 is a partial longitudinal section of a modified form of the engine.

Referring to the form of the invention shown in Figs. 1 to 5, the engine therein shown is provided with a crank case 1, on which is journaled the engine shaft 2 (see Fig. 1); said crank case also serving as a

support for the cylinder means of the engine.

It will be understood that the invention is applicable to an engine with any number of cylinders, it being herein illustrated as applied to a single cylinder engine, the working or main cylinder 3 being provided with a cylinder extension or low pressure cylinder 4 axially in line therewith, and opening directly into the crank case 1. The main piston 5, working in cylinder 3, is provided with a flange or enlargement 8, working in the cylinder 4, which is sufficiently larger than the main cylinder 3 to form an annular low pressure cylinder chamber 9 between the wall of cylinder 4 and the body 70 of piston 5. Pistons 5 and 8 are provided with the usual packing rings 10 and 10'. The crank case 1 is provided with a spring controlled inwardly opening inlet valve 6, and a pipe or duct 7 leads from the crank case to a port 16 in the cylinder 3.

The main cylinder is provided with exhaust port 17 and scavenging inlet port 16, located near the outer end of the cylinder so as to be opened by the piston 5 as it approaches the outer end of its stroke. Cylinder 3 is also provided with an inlet port 12 for mixture of fuel and air, and for a supply of low pressure air for positive scavenging, said inlet port being located at the inner or head end of the cylinder, for example, in the head 13 of the cylinder. An inwardly opening puppet valve 14 controls communication between a valve chamber 15 in the head 13, and the interior of the cylinder 3, said valve being normally held closed by a spring 18 whose tension may be adjusted by means 19, so that the valve will open only under a definite excess of pressure in the valve chamber over the pressure in the cylinder.

Main cylinder 3 is also provided with a supplementary exhaust port 20 located in position to be closed by the piston during the inward stroke thereof, say at about half stroke, this port communicating with an exhaust passage 21, having an inwardly opening valve 22, which is normally held closed by a spring 27 and is opened by positively acting means operated by the engine, for example, by a lever 23, connected by rod 24 to an eccentric 26 on a shaft 28, which is connected by chain gearing 30 or otherwise, to

the main shaft 2 of the engine, so as to rotate in synchronism therewith.

Means are provided for supplying a mixture of fuel and compressed air in the valve chamber 15, and also for supplying to said chamber compressed air at relatively low pressure, before and during the admission of the fuel and air mixture thereto. The fuel and air supply means comprises a pump 32 having its intake valve 33 connected by pipe 33' with a carbureter 34 or any other means for furnishing fuel and air; the outlet valve 35' of said pump communicating through a pipe 35, a mixing chamber 36 and an outlet pipe 31, with the inlet valve chamber 15 for cylinder 3. This pump 32 may comprise a cylinder in which works a piston 29, operated by an eccentric 25 on shaft 28 above referred to. The pump 32 is adapted, at each upstroke of its piston, to draw in a charge of air and fuel through the carbureter 34, and in the next downstroke, to compress this mixture of fuel and air to a high pressure, say eighty to one-hundred pounds per square inch, the mixture of air and fuel being heated by this compression sufficiently to temporarily hold the fuel in the form of a gas. The outlet pipe 35 for said pump is made of such small diameter that the discharge from the pump will travel therethrough at high velocity, and will retain its temperature and state of mixture until it reaches the mixing chamber 36, where it is mixed with a further quantity of air, as hereinafter described.

The outlet 35" of pipe 35 is normally closed by a pop-valve 37, (Fig. 5) controlled by a spring 38 which is set to allow the valve to open only at a relatively high pressure, say eighty to one hundred pounds per square inch. The pressure of this spring may be adjusted by a cap 39 bearing thereon and screwing on a support 40. A low pressure air supply pipe 41 also opens into this mixing chamber and in order to insure thorough mixture of the fuel and air, the mixing chamber is preferably of the circular form shown, with the low pressure air pipe 41 entering the same tangentially, and the outlet 35" for the fuel and air pipe 35 extending axially in the chamber 36, so that when the pop-valve 37 is suddenly opened by the pressure of the compressed mixture of fuel and air, this mixture is violently ejected in the form of a radial sheet or spray, into the tangentially moving current of air in the chamber 36, and is then drawn out through the outlet 31 leading to the valve chamber 15, said outlet being axially arranged, with respect to the chamber 36, so that it is at the center of the vortex set up in the chamber, and therefore at the point of most violent agitation.

The low pressure air pipe 41 leads from a storage chamber 43 which communicates with

the low pressure cylinder chamber 9, through a port 44 controlled by an outwardly opening puppet valve 45, normally held closed by a spring 46. Said low pressure cylinder is provided with an inlet port 47 communicating with a valve chamber 47' said port 47 being controlled by an inwardly opening inlet valve 48, normally held closed by a spring 49. Valve chamber 47' has an intake 50 for air, controlled by a throttle 51, which is connected to a governor 52 by any suitable means, for example by lever and link connections 52', 53, 54 between throttle 51 and a shaft 55, and lever and link connections 56, 57, 58, between said shaft and the governor. The governor may be driven by the shaft 28 above referred to. Governor 52 may also, through connections 61 and 62, control a throttle 63 for the carbureter 34.

Any suitable means is provided for igniting the compressed charge in the main cylinder, for example, a spark plug 60, and means for producing a spark thereat at the proper time.

The operation is as follows: At each stroke of the piston 5 in an inward direction, that is, toward the head of the cylinder, there is a condition of suction produced in the crank case 1, and the inlet valve 6 opens, allowing air to be drawn into the crank case. During this inward stroke, also, air, is being compressed in the low pressure cylinder chamber 9, say to a pressure of three to five pounds per square inch, and is forced into the storage chamber 43 and the pipe 41 connected thereto, but is prevented from passing into the cylinder 3 by the valve 14, which at this time is held closed by the pressure in said cylinder and by its spring 18. In the next succeeding outward stroke of the piston 5, the valve 6 is closed by its spring, and the piston compresses the air in the crank case until it has nearly reached the end of the outstroke, when it opens the ports 16 and 17, allowing air to pass from the crank case through pipe 7 and port 16 to the cylinder 3, this air being blown through the cylinder so as to effect a preliminary scavenging. At the moment the pressure in the cylinder 3 falls, by reason of the escape of gases therefrom through the exhaust port 17, the air inlet valve 14 starts to open under the pressure of the compressed air from storage chamber 43, and such compressed air then passes through said valve and blows through said cylinder, scavenging the cylinder with a positive action. While the piston 5 is at the outer portion of its stroke, for example, before it has closed the exhaust port 17, the supplementary exhaust valve 22 is opened by action of eccentric 26, so that fresh air entering at valve 14 may continue to scavenge the cylinder during the first portion of the instroke, thereby prolonging the period of exhaust 130

and enabling more thorough scavenging. The pump 32 is so timed in its action, relatively to the piston 5, that during this outer portion of the instroke of the piston said pump will compress a mixture of air and fuel to a condition of high pressure, and correspondingly high temperature and will force such compressed hot mixture through the pipe 35 to the pop valve 37 of the mixing chamber 36, and when the pressure reaches a definite predetermined amount, say eighty pounds per square inch, said pop valve will suddenly open allowing the compressed mixture to issue violently into the 15 mixing chamber in the form of a radial spray or sheet of mixture, in the path of the blast of compressed air passing through the mixing chamber from the storage chamber 43 to the cylinder 3, and as this current of 20 air is moving vertically or in a whirling manner, at high velocity, it takes up the rich mixture thus discharged into it and mixes it thoroughly with the low pressure air from pipe 41, the resultant mixture then passing 25 through the duct 31 and valve 14 to cylinder. 3. The pump 32 is of relatively small capacity compared to the main cylinder 3 and the cylinder chamber 9, as it is only necessary to compress therein a small portion of 30 the total charge, including only sufficient air to carry and vaporize the liquid fuel. By reason of this small capacity of the said pump, it is possible to compress the mixture therein to the stated high pressure without 35 expending an undue proportion of the work done by the main cylinder. Moreover, by reason of the relatively small amount of air so compressed with the fuel, the mixture of fuel and air so compressed in the pump 32 is 40 sufficiently rich to prevent it from being prematurely ignited by the heat due to compression in said pump, but forms an explosive mixture when diluted with the fresh air in the main cylinder. I prefer to so time the 45 operation of the parts aforesaid that this mixture entering the cylinder will reach the supplementary exhaust port 20 at about the same time that the piston 5 closes said port, thereby insuring a clean full charge in the 50 compression chamber of cylinder 3, without waste of fuel. The further inward movement of piston 5 then compresses the charge, this compression beginning at the moment that the valve 22 closes and continuing until 55 the end of the inward stroke so that only the latter portion of the instroke, say one half stroke, of the piston is used for compression. The piston thus compresses, say one half a charge in the cylinder 3 and I prefer to 60 make the clearance in the cylinder such that with this half charge, the pressure at full compression will rise to, or somewhat higher than the usual high compression, say seventy pounds per square inch. At or about 65 the time of full compression, at the inner

end of the stroke, the charge is ignited by the ignition means 60, with the result that the piston is driven outwardly by the expansion of the burning gases. During the expansion stroke the supplementary exhaust valve 22 is held closed, so that exhaust does not begin until the piston opens the port 17 at the end of the stroke.

It will be noted that compression does not begin until the piston has moved a considerable distance on its instroke, but that expansion continues during substantially the whole outstroke, so that the effect is to increase the ratio of expansion relatively to the compression, and I prefer to so increase this ratio that the exhaust gases are discharged at substantially atmospheric pressure, thereby eliminating the waste due to high terminal pressure at the exhaust. This gives a high fuel economy and I am also enabled to further increase the fuel economy by increasing, if desired, the compression in the cylinder 3, beyond the usual limitations. This effect I secure by decreasing the charge and decreasing the clearance 90 in greater ratio than the decrease of charge, so that the combustion chamber is shortened and the time of exposure of the hot gases to the metal of the cylinder is correspondingly reduced, so that a high compression may be used without liability of premature ignition. The decrease in clearance enables the decreased charge to be compressed to a higher pressure, and the shortening of the compression stroke enables this 95 higher compression to be effected without premature ignition; the increase of heating effect due to greater compression being offset by the decrease in absorption of heat from the wall of the cylinder. 100

In applying the invention to direct acting pumps or compressors, where crank case compression is not available, I may, as shown in Fig. 7, provide a trunk cylinder 64 on the end of the cylinder extension 4, 110 said trunk cylinder having an inlet valve 6, and serving as a compression cylinder for scavenging air, which is discharged to the main cylinder through a duct 7 as above described. The piston rod 65 for the pump or 115 compressor passes through a stuffing box in the head of this trunk cylinder.

What I claim is:

1. In an internal combustion engine, a cylinder having inlet connection for combustible mixture, and exhaust connections for products of combustion, means for supplying scavenging air through said inlet connections and for subsequently supplying mixture through said inlet connections, during the inward stroke of the piston, a piston working in said cylinder, means for maintaining the exhaust connections open during a part of the inward stroke of the piston, to permit scavenging, for then closing said ex- 130

haust connections to permit compression during the latter part of the inward stroke of the piston, and for maintaining the exhaust connections closed during substantially the full outward stroke of the piston.

2. In an internal combustion engine, the combination of a cylinder, a piston working therein, said cylinder being provided with exhaust and scavenging inlet ports in position to be opened by the piston at the end of its expansion stroke, and being provided with an inlet port for mixture and for scavenging air and with a supplementary exhaust port in position to remain open during a portion of the inward stroke of the piston, means for supplying air through said mixture inlet port during the first part of the compression stroke while the supplementary exhaust port is open, and means for supplying combustible to such air during the latter part of the supply thereof, a valve controlling said supplementary exhaust port and operated by the engine to open said port during the first portion of the inward stroke of the piston and to close said port during the rest of the inward stroke and during substantially the full outward stroke of the piston.

3. In an internal combustion engine, a cylinder, a piston working therein, said cylinder being provided with exhaust and scavenging inlet ports adapted to be opened by the piston at the end of the expansion stroke, and said cylinder being provided with a mixture inlet port and with a supplementary exhaust port in position to remain open during the first part of the compression stroke of the piston, a valve for said supplementary exhaust port operated by the engine to open said port during the first part of the compression stroke and to close said port during the latter part of the compression stroke and substantially all of the expansion stroke, a valve for the aforesaid mixture inlet port adapted to open during the time of opening of said supplementary exhaust valve, and means for supplying scavenging air and subsequently supplying combustible mixture to said mixture inlet port when its valve is opened.

4. In an internal combustion engine, the combination of a cylinder, a piston working therein, said cylinder being provided with an inlet for combustible mixture and for scavenging air, with an exhaust port and a preliminary scavenging inlet port adapted to be opened by the piston when at the outer end of its stroke, and with a supplementary exhaust port positioned to remain open during a portion of the inward stroke of the piston, and engine operated valve means for closing said supplementary exhaust port during the outward stroke and the latter portion of the inward stroke of the piston, and for opening said port during the first

portion of the inward stroke of the piston so as to prolong the period of exhaust and to reduce the period of compression so that it is shorter than the period of expansion, means for supplying scavenging air to said preliminary scavenging inlet port when it is opened by the piston, means for supplying scavenging air to said inlet port for combustible mixture and for scavenging air during the first part of the inward stroke of the piston and means for supplying combustible mixture to said inlet port during a later portion of said stroke.

5. In an internal combustion engine, the combination of a cylinder, a piston working therein, said cylinder being provided with a spring controlled inlet, means for supplying to said inlet compressed air for scavenging and for subsequently supplying to said inlet a charge of combustible mixture, said cylinder being also provided with an exhaust port and with a preliminary scavenging inlet port, both positioned to be opened by the piston substantially at the outer end of its travel, and said cylinder being provided with a supplementary exhaust connection and means for opening the same during the first part of the inward stroke of the piston and to close such connection during the remainder of such inward stroke and during the outward stroke of the piston.

6. In an internal combustion engine, the combination with a cylinder and a piston working therein, said cylinder having an inlet and provided with an exhaust connection opened when the piston completes its outward stroke, means operated by the engine for compressing air, a valve controlling communication between said air compressing means and said inlet for the cylinder, to admit air to the cylinder when the pressure falls therein on opening the exhaust port, and a pump operating periodically to receive and compress a definite charge of air and fuel and force the same into the compressed air passing to the cylinder, after a portion of such compressed air has passed into the cylinder for scavenging.

7. In an internal combustion engine, a combustion cylinder, a piston working therein, means for supplying fresh air to the cylinder at the beginning of the compression stroke, a pump of small capacity relatively to said cylinder, means for supplying a mixture of air and liquid fuel to said pump, said pump having its outlet connected to the fresh air supply means for said cylinder, and said pump being connected for operation by said piston to cause a mixture of liquid fuel and air to be compressed therein to sufficient pressure to vaporize the liquid fuel by the heat of compression and to force the compressed mixture into the fresh air passing to the cylinder.

8. In an internal combustion engine, a

cylinder and a piston working therein, said cylinder having an exhaust port opened at the end of the expansion stroke, means for compressing air at low pressure, means for admitting such compressed air to the said cylinder during the compression stroke, and a pump having its outlet connected to the means for admitting air to said cylinder and having its inlet provided with means for supplying a mixture of air and liquid fuel, said pump being of relatively small capacity compared to said cylinder and being connected for operation by the engine during the compression stroke to compress the mixture of air and liquid fuel to sufficiently high pressure to vaporize the fuel by the heat of compression, and to force such compressed mixture, while still at high temperature, into the air passing to said cylinder during the compression stroke.

9. An internal combustion engine comprising a cylinder, provided with an exhaust port and a scavenging inlet port, a piston working in said cylinder and opening said ports at the outer end of the outward stroke, means operated by the piston in its outward stroke, for compressing air, said air compressing means communicating with said scavenging inlet to blow compressed air through the inlet when said ports are opened, air compressing means operated by the piston on its inward stroke, and storage means connected thereto to receive and store the compressed air till the end of the next outward stroke, a valve controlling communication between said last named air compressing means and the cylinder, said valve opening automatically under the pressure of such air to admit such compressed air to the cylinder when the pressure therein falls on opening of the exhaust valve, and

means for supplying combustible material to the compressed air passing to said valve, after a portion of the compressed air has passed through said valve.

10. An internal combustion engine comprising a cylinder, provided with an exhaust port and a scavenging inlet port, a piston working in said cylinder and opening said ports at the end of its outstroke, means operated by the piston, in its outstroke, for compressing air said means communicating with said scavenging inlet port to blow air through the cylinder when said ports are opened, inlet valve means for the engine and air compressing means communicating therewith and operated by the piston on its inward stroke, said valve means being adapted to open automatically when the pressure in the cylinder falls on opening of the exhaust valve, to admit compressed air to the cylinder, means for supplying compressed combustible mixture to the air passing to said inlet valve means, after a portion of the compressed air has passed therethrough, and supplementary exhaust connections for the cylinder, provided with a valve operated by the engine and opened during the first part of the instroke to prolong the period of exhaust, while the compressed air is passing into the cylinder, to scavenge the same, and closed during the remainder of the instroke to permit of compression of the charge and also closed during the expansion stroke.

In testimony whereof I have hereunto set my hand, at Los Angeles, California, this 22nd day of June 1914.

FRANK J. KIMBALL.
